CLAIM

The ornamental design for a sitting posture correction belt, as shown and described.

DESCRIPTION

FIG. 1 is a front elevational view of a sitting posture correction belt showing my new design;

FIG. 2 is a rear view thereof;

FIG. 3 is a left side view thereof;

FIG. 4 is a right side view thereof;

FIG. 5 is a front perspective view shown in a position of use thereof;

FIG. 6 is a side perspective view shown in a position of use thereof;

FIG. 7 is an enlarged detailed view taken from the encircled area labeled 7 in FIG. 1; and,

FIG. 8 is an enlarged detailed view taken from the encircled area labeled 8 in FIG. 5.

The broken lines shown in the drawings depict portions of the sitting posture correction belt that form no part of the claimed design.
